DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

FURNACE WALL.

Application filed April 2, 1925. Serial No. 20,026.

My present invention relates to improvements in furnace walls, and particularly of the type in which air-cooling spaces are provided on the exterior of the wall through which air may be passed to cool the wall, and will best be understood from the following description and the annexed drawings, in which Fig. 1 is a view from the inside of a portion of a wall embodying my invention; Fig. 2 is a section on the line 2—2 of Fig. 1; Fig. 3 is a section on the line 3—3 of Fig. 1; Fig. 4 is an enlargement of a portion of Fig. 3; Fig. 5 is a view similar to Fig. 1, but showing a modification; Fig. 6 is a section on the line 6—6 of Fig. 5; Fig. 7 is a section on the line 7—7 of Fig. 5; Fig. 8 is an enlargement of a portion of Fig. 7; Fig. 9 is a view similar to Fig. 3, but showing a modification; Fig. 10 is a section on the line 10—10 of Fig. 9; Fig. 11 is an enlargement of a portion of Fig. 9 and similar to Fig. 4, but showing a modification; Fig. 12 is a view similar to Fig. 1 and showing still another modification; Fig. 13 is a section on the line 13—13 of Fig. 12; Fig. 14 is a section on the line 14—14 of Fig. 12; Fig. 15 is an enlargement of a portion of Fig. 14, and Fig. 16 is a section on the line 16—16 of Fig. 15.

Like reference characters indicate like parts throughout the drawings.

It will be understood that in each of the constructions illustrated, while I have shown only a portion of a wall in each case, the entire wall, regardless of its extent, will be made up of duplications of the portion illustrated and that in a furnace having, say, a rectangular cross-section, as many of the vertical walls of the furnace as is desired may be made up in the manner illustrated.

In the arrangement shown in Figs. 1 to 4, inclusive, the wall proper 10 is made up of the usual courses of refractory brick or tile, as the case may be, the wall being provided with one or more courses of special tile 11, which, in the form illustrated, are provided with grooves, so that when a pair of the tiles 11 are placed side by side, a T-shaped groove is provided with the neck of the groove extending to the rear of the tile and the enlargement between the front and the rear of the tile. It should also be noted that while I refer to this recess as "T-shaped," any form of recess in which there is an enlargement between the front and the rear of the

tile is to be understood as being covered by that phrase.

Outside of the wall and extending vertically is a series of spaced fixed members which, in the form shown in Fig. 1, are I-beams 12 having a web of sufficient height so that when one flange of the I-beam is against the refractory wall, the other flange will be sufficiently spaced therefrom to provide the desired width of air duct on the outside of the refractory wall. The space between the I-beams 12 is filled with a casing 13, and, as will be best seen by an inspection of Fig. 3, each pair of I-beams 12 with the casing 13 and the refractory wall constitutes a vertical air duct through which air may pass to cool the outside of the wall.

In the recesses formed between each pair of tile 11 is a bulb piece 14 with an enlarged head 15 engaging the enlarged inner end of the recess and with the shank of the bulb piece extending through the narrow part of the recess and into the air duct just referred to. The outer end of the bulb piece is provided with a hook portion 16, the recess of which preferably extends vertically to the top of the bulb piece 14. In this recess of the hook rests a horizontal bar 17 which, in the form shown in Figs. 1 to 4, inclusive, is simply a bar of rectangular cross-section. The recesses forming the hooks 16 are positioned in the several bulb pieces so that, when the bar 17 rests behind the hooks 16, its ends will be positioned against the inner surface of that flange of the I-beam 12 which contacts with the refractory wall. Preferably the tile 11 and the bulb pieces 14 are of approximately the same height, though, if desired, the bulb pieces may be made of a less height to permit vertical motion thereof in the tile 11.

In the arrangement described, the wall is free to expand in any direction in a vertical plane, the lateral expansion being permitted by the sliding of the bulb pieces 14 along the horizontal member 17. The vertical motion is permitted by the sliding of the bar 17 along the flange of the I-beam 12. The wall is built with the bulb pieces 14 in place and the bar 17 is then dropped into place and is supported on the bulb pieces 14. This provides a very easy method of building the wall, since there are no parts to be connected by rivets or the like, while, at the same time, the wall will be held against in-

ward motion and yet be free to move in any direction in a vertical plane.

The arrangement shown in Figs. 5 to 8, inclusive, is similar to that just described, except that provision is made for horizontal air ducts instead of vertical air ducts. In this form, the fixed I-beams 18 extend horizontally in spaced relation, the casing 13 and the wall 10 forming the other sides of the horizontal air duct. At spaced intervals I have shown fixed vertical members 19 each made up of a pair of angle-irons with their ends connected through suitable angles with the horizontal I-beams 18. As before, the ends of the horizontal bar 17 rests against the inner side of that flange of the fixed members 19 which is against the refractory wall and the bar 17 is free to slide on this flange to permit the desired vertical motion of the wall, the desired horizontal motion being provided as before by the sliding of the bulb pieces 14 on the bar 17 and the bar 17 by its contact with the fixed members 19, preventing the motion of the wall toward the furnace.

In each of the arrangements just described, the wall is held only against motion toward the furnace except where it bears on the fixed members. In some cases, it is desirable to hold it more effectively against possible outward motion by holding each of the special tiles 11 against such outward motion. This I provide for in the arrangement shown in Figs. 9, 10 and 11 by attaching to the web 35 of the I-beam 12 an angle piece 20 abutting against the outer side of the bar 17 and, therefore, preventing the motion of the bar in a direction away from the refractory wall. As will be best seen in Fig. 11, the bar 17 will 40 thus be held against motion in either direction at right-angles to the surface of the wall and that of the wall, therefore, will be held against both inward and outward motion throughout its entire width. Since the possible vertical motion of the bar 17 is a short one, the angle pieces 20 need have no considerable height, as shown in Fig. 10.

In Figs. 12 to 16, inclusive, I have shown an arrangement for holding the wall against horizontal motion in either direction, in this case, the horizontal bar 21 being formed of an angle-iron, one flange of which rests on the hook recess of the bulb piece 14 and the other rests on top of the hooks 16. The ends 55 of this angle-iron are held between the flanges of the small vertical I-beams 22 and angle pieces 23 attached to the web of the I-beams 22. In this arrangement, the air ducts are horizontal and are formed by the casing 13, the refractory wall and the fixed horizontal I-beams 24, to which the vertical I-beams 22 are attached in any suitable manner.

It will be understood that the arrangements which I have shown are merely illus-

trative and that the embodiment of my invention may be widely varied. It will also be understood that while I have described the usual arrangement in which the courses of special tile 11 extend horizontally, these courses may be made to extend vertically, in which case the entire arrangement would be turned through 90°, and I intend in the appended claims to cover such an arrangement. 75

I claim:

1. In an air-cooled furnace wall, a plurality of substantially parallel fixed members spaced apart, a casing on the outer side of said fixed members and a wall on the inside of said fixed members, whereby air ducts are formed between said fixed members, said wall being provided with a horizontal row of tile having vertically disposed T-shaped recesses therein, a horizontal member at the outer side of said wall and contacting with said fixed members to prevent motion of said horizontal member toward said wall, and bulb pieces engaging said recesses and said horizontal member. 90

2. In an air-cooled furnace wall, a plurality of substantially parallel fixed members spaced apart, a casing on the outer side of said fixed members and a wall on the inside of said fixed members, whereby air ducts are formed between said fixed members, said wall being provided with a horizontal row of tile having vertically disposed T-shaped recesses therein, a horizontal member at the outer side of said wall and contacting with said fixed members to prevent motion of said horizontal member toward said wall, and bulb pieces engaging said recesses and said horizontal member, said horizontal member being free to move vertically with the row of tile when the wall expands vertically. 100

3. In an air-cooled furnace wall, a plurality of substantially parallel fixed members spaced apart, a casing on the outer side of said fixed members and a wall on the inside of said fixed members, whereby air ducts are formed between said fixed members, said wall being provided with a horizontal row of tile having vertically disposed T-shaped recesses therein, a horizontal member at the outer side of said wall and contacting with said fixed members to prevent motion of said horizontal member toward said wall, bulb pieces engaging said recesses and said horizontal member, said horizontal member being free to move vertically with the row of tile when the wall expands vertically, and means to prevent said horizontal member from moving in a direction away from the wall. 110

4. In an air-cooled furnace wall, a plurality of fixed substantially parallel members spaced apart, a casing on the outer side of said fixed members and a wall on the inside 130

of said fixed members, whereby air ducts are formed between said fixed members, said wall being provided with a horizontal row of tile having vertically disposed T-shaped recesses therein, bulb pieces engaging said recesses and having a hooked end extending into said air ducts, and a horizontal bar having its ends held by said fixed members against motion toward said wall and engaging the hooks of said bulb pieces.

5. In an air-cooled furnace wall, a plurality of substantially parallel fixed members spaced apart, a casing on the outer side of said fixed members and a wall on the inside 15 of said fixed members, whereby air ducts are formed between said fixed members, said wall being provided with a horizontal row of tile having vertically disposed T-shaped recesses therein, bulb pieces engaging said recesses and having a hooked end extending into said air ducts, and a horizontal bar having its ends held by said fixed members against motion toward said wall and engaging the hooks of said bulb pieces, said hooks 20 extending upwardly and said horizontal bar resting in said hooks.

6. In an air-cooled furnace wall, a plurality of substantially parallel fixed members spaced apart, a casing on the outer side of 25 said fixed members and a wall on the inside of said fixed members, whereby air ducts are formed between said fixed members, said wall being provided with a horizontal row of tile having vertically disposed T-shaped 30 recesses therein, bulb pieces engaging said recesses and having a hooked end extending into said air ducts, and a horizontal bar having its ends held by said fixed members against motion toward said wall and engaging the hooks of said bulb pieces, said hooks 35 extending upwardly and said horizontal bar resting in said hooks, said bar being free to move vertically.

7. In an air-cooled furnace wall, a plurality of substantially parallel fixed members spaced apart, a casing on the outer side of 40 said fixed members and a wall on the inside of said fixed members, whereby air ducts are formed between said fixed members, said 45 wall being provided with a horizontal row of tile having vertically disposed T-shaped recesses therein, bulb pieces engaging said recesses and having a hooked end extending into said air ducts, and a horizontal bar having its ends held by said fixed members 50 against motion toward said wall and engaging the hooks of said bulb pieces, said hooks extending upwardly and said horizontal bar resting in said hooks, said bar being free to 55 move vertically, and means to prevent movement of said bar in a direction away from the wall.

8. In an air-cooled furnace wall, a refractory wall having a horizontal row of tile 60 provided with vertically disposed T-shaped

recesses on the outer side of the wall, a casing spaced from the outer side of the wall, vertically disposed fixed members in the space between the wall and the casing, bulb pieces 70 engaging said recesses and having hooked ends extending into the space between the wall and the casing, and a horizontal bar having its ends resting against said fixed members so as to prevent motion of the bar in a direction toward the wall, and so as to be free to move vertically with the hooks of 75 said bulb pieces engaging said bar.

9. In an air-cooled furnace wall, a refractory wall having a horizontal row of tile 80 provided with vertically disposed T-shaped recesses on the outer side of the wall, a casing spaced from the outer side of the wall, vertically disposed fixed members in the space between the wall and the casing, bulb pieces 85 engaging said recesses and having hooked ends extending into the space between the wall and the casing, and a horizontal bar having its ends resting against said fixed members so as to prevent motion of the bar in a direction toward the wall and so as to be free to move vertically with the hooks of 90 said bulb pieces engaging said bar, the hooks of said bulb pieces extending upwardly and said horizontal bar being supported by said hooks.

10. In an air-cooled furnace wall, a refractory wall having a horizontal row of tile 95 provided with vertically disposed T-shaped recesses on the outer side of the wall, a casing spaced from the outer side of the wall, vertically disposed fixed members in the space between the wall and the casing, bulb pieces 100 engaging said recesses and having hooked ends extending into the space between the wall and the casing, a horizontal bar having its ends resting against said fixed members so as to prevent motion of the bar in a direction toward the wall and so as to be free to move vertically with the hooks of 105 said bulb pieces engaging said bar, and means to prevent motion of the bar in a direction away from the wall.

11. In an air-cooled furnace wall, a refractory wall having a horizontal row of tile 110 provided with vertically disposed T-shaped recesses on the outer side of the wall, a casing spaced from the outer side of the wall, a plurality of vertically disposed fixed I-beams extending from the wall to the casing and spaced apart to form air ducts therebetween, the webs of said I-beams being at right-angles to the face of the wall, bulb pieces 115 engaging said recesses and having hooked ends extending into said air ducts, and a bar having its ends resting against the outer side of the flange of the I-beams adjacent the wall and the hooks of the bulb pieces 120 engaging said horizontal bar.

12. In an air-cooled furnace wall, a refractory wall having a horizontal row of 125

- tile provided with vertically disposed T-shaped recesses on the outer side of the wall, a casing spaced from the outer side of the wall, a plurality of vertically disposed fixed I-beams extending from the wall to the casing and spaced apart to form air ducts therebetween, the webs of said I-beams being at right-angles to the face of the wall, bulb pieces engaging said recesses and having hooked ends extending into said air ducts, and a bar having its ends resting against the outer side of the flange of the I-beams adjacent the wall and the hooks of the bulb pieces engaging said horizontal bar, said hooks extending upwardly and said horizontal bar being supported on said hooks, and a holding member connected to each I-beam to prevent motion of the ends of said horizontal bar away from the wall.
13. In an air-cooled furnace wall, a refractory wall having a horizontal row of tile provided with vertically disposed T-shaped recesses on the outer side of the wall, a casing spaced from the outer side of the wall, a plurality of vertically disposed fixed I-beams extending from the wall to the casing and spaced apart to form air ducts therebetween, the webs of said I-beams being at right-angles to the face of the wall, bulb pieces engaging said recesses and having hooked ends extending into said air ducts, a bar having its ends resting against the outer side of the flange of the I-beams adjacent the wall and the hooks of the bulb pieces engaging said horizontal bar, and a holding member connected to each I-beam to prevent motion of the ends of said horizontal bar away from the wall.
14. In an air-cooled furnace wall, a refractory wall having a horizontal row of tile provided with vertically disposed T-shaped recesses on the outer side of the wall, a casing spaced from the outer side of the wall, a plurality of vertically disposed fixed I-beams extending from the wall to the casing and spaced apart to form air ducts therebetween, the webs of said I-beams being at right-angles to the face of the wall, bulb pieces engaging said recesses and having hooked ends extending into said air ducts, a bar having its ends resting against the outer side of the flange of the I-beams adjacent the wall and the hooks of the bulb pieces engaging said horizontal bar, said hooks extending upwardly and said horizontal bar being supported on said hooks, and a holding member connected to each I-beam to prevent motion of the ends of said horizontal bar away from the wall.
15. In an air-cooled furnace wall, fixed members spaced apart, a casing along one edge of said members and a wall along the other edge, said members, casing and wall forming air ducts, said wall comprising tile having recesses therein, transverse members engaging said fixed members and slideable thereon, and holding members engaging said recesses and said transverse members.
16. In an air-cooled furnace wall, fixed members spaced apart, a casing along one edge of said members and a wall along the other edge, said members, casing and wall forming air ducts, said wall comprising tile having recesses therein, transverse members engaging said fixed members and slideable thereon, and holding members engaging said recesses and said transverse members.
17. In an air-cooled furnace wall, fixed members spaced apart, a casing along one edge of said members and a wall along the other edge, said members, casing and wall forming air ducts, said wall having recesses therein, transverse members engaging said fixed members and slideable thereon, and holding members engaging said recesses and said transverse members.
18. In an air-cooled furnace wall, fixed members spaced apart, a casing along one edge of said members and a wall along the other edge, said members, casing and wall forming air ducts, said wall having recesses therein, transverse members engaging said fixed members and slideable thereon, and holding members engaging said recesses and said transverse members and slideable along said transverse members.

DAVID S. JACOBUS.
